UNITED STATES PATENT OFFICE.

ELMER H. CLARK, OF SHELDON, IOWA.

ATTACHMENT FOR MAIL-BOXES.

1,018,128.

Specification of Letters Patent.

Patented Jan. 2, 1912.

Application filed April 13, 1911. Serial No. 620,919.

To all whom it may concern:

Be it known that I, ELMER H. CLARK, a citizen of the United States, residing at Sheldon, in the county of O'Brien and State of Iowa, have invented certain new and useful Improvements in Attachments for Mail-Boxes; and I do declare the following to be a full, clear, and exact description of the invention, such as will enable others skilled 10 in the art to which it appertains to make and use the same.

This invention relates to improvements in mail holding attachments for mail boxes.

One object of the invention is to provide 15 an attachment of this character by means of which letters or other mail may be held in position to be readily taken by the carrier or collector thereby obviating the loss of time which is required in picking up the 20 several pieces of mail when thrown loosely onto the bottom of the box.

Another object is to provide a mail holding attachment of this character which will be simple, strong, durable and inexpensive 25 in construction and which may be readily secured in any form of mail box.

With these and other objects in view the 30 invention consists of certain novel features of construction, combination and arrangement of parts as will be more fully described and particularly pointed out in the appended claim.

In the accompanying drawings: Figure 1 is a perspective view of a portion of a 35 mail box showing my improved mail holding attachment arranged therein; Fig. 2 is a front view of the attachment removed from the box, parts of the same being broken away to illustrate more clearly the 0 manner in which the clamping member of the attachment is secured. Fig. 3 is a vertical sectional view on the line 3—3 of Fig. 2; Fig. 4 is a cross sectional view on the line 4—4 of Fig. 2.

5 In the embodiment of the invention I provide an attaching plate 1, which has its opposite side edges bent inwardly at right angles and thence laterally to form attaching flanges 2, which are adapted to be bolted, riveted or otherwise firmly secured to the inner side of the mail box 3 at any desired position therein.

Adapted to be secured to the outer side of the attaching plate 1 is a spring clip or clamping member 4, said member being preferably constructed from a single piece

of spring wire rod bent midway between its ends to form an elongated loop 5, said loop being preferably bent transversely in the form of a band curved as shown in Fig. 3 60 of the drawing. The ends of the rod after forming the loop 5 are bent to form spring coils 6 after which said ends are extended longitudinally a short distance and then bent inwardly at a right angle to form attaching members 7. In arranging the clip 4 the loop 5 is engaged with the outer side of the attaching plate 1 and over the attaching members 7 is arranged a fastening plate 8, said plate being riveted or otherwise rigidly secured to the outer side of the lower end of the plate 1. The ends of the plate 8 are bent at right angles and engage the opposite sides or edges of the plate 1 as shown. In the inner side of the plate 8 and 75 adjacent portion of the plate 1 are preferably formed grooves or channels 9 with which are engaged the fastening members 7 of the clip whereby when the plate 8 is fastened to the plate 1 in the manner described 80 the fastening members 7 will be rigidly secured and will firmly hold the clip in position on the plate 1.

By offsetting the attaching plate 1 from the side of the box to which the same is secured it will be readily seen that the letters or other mail held between said plate and the clip 5 will be spaced from the side of the box and may thus be readily gripped by the carrier. This offsetting of the attaching 85 plate 1 causes it to form a pocket when secured to the wall of the mail box in which newspapers, magazines, and the like may be inserted, the clip being used to hold letters. It will be noted that the upper end of the 90 loop 5 of the clip projects a slight distance above the upper edge of the plate 1 and that said upper end is curved outwardly to a slight extent. This arrangement of the upper end of the clip facilitates the engagement of mail between the same and the attaching plate 1; and further provides means which can be conveniently gripped by the hand of the operator for releasing the tension of the clip upon the mail.

100 By providing my improved mail holding attachment it will be readily seen that the carrier upon opening the box may drop the mail to be delivered into the same and readily take the mail from the holding attachment 110 thus obviating the annoyance and loss of time which is usually necessary in pick-

ing up the letters and other mail matter scattered over the bottom of the box, this operation requiring the removal of the carrier's glove and necessitating other delays 5 which are entirely dispensed with by the use of the holding attachment herein shown and described.

From the foregoing description taken in connection with the accompanying drawings, the construction and operation of the 10 invention will be readily understood without requiring a more extended explanation.

Having thus described my invention, what I claim is:

15 A mail holding attachment for mail boxes adapted to separately hold letters and papers and located within the box and secured

to the rear wall thereof, said holding attachment comprising a pocket open at its upper end, and an elongated clamping loop 20 yieldingly secured to the front wall of the pocket adjacent to the bottom thereof, the medial upper portion of the clamping loop extending above the upper edge of the pocket, whereby the projecting looped portion of the clip is in convenient position to be operated.

In testimony whereof I have hereunto set my hand in presence of two subscribing witnesses.

ELMER H. CLARK.
